US00D601583S

(12) **United States Design Patent**
Andre et al.

(10) **Patent No.:** **US D601,583 S**
(45) **Date of Patent:** **** Oct. 6, 2009**

(54) **MEDIA DEVICE**

(75) Inventors: **Bartley K. Andre**, Menlo Park, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, San Francisco, CA (US); **Matthew Dean Rohrbach**, San Francisco, CA (US); **Douglas B. Salzger**, Menlo Park, CA (US); **Calvin O. Seid**, Palo Alto, CA (US); **Christopher J. Stringer**, Portola Valley, CA (US); **Eugene Anthony Whang**, San Francisco, CA (US); **Rico Zorkendorfer**, San Francisco, CA (US); **Steve Jobs**, Palo Alto, CA (US)

(73) Assignee: **Apple Inc.**, Cupertino, CA (US)

(**) Term: **14 Years**

(21) Appl. No.: **29/265,955**

(22) Filed: **Sep. 11, 2006**

(51) LOC (9) Cl. **14-03**

(52) U.S. Cl. **D14/496**

(58) Field of Classification Search .... **D14/496, D14/401, 435, 474, 483, 217, 137, 138, 160, D14/168; 345/156, 169, 173-179, 905; 715/727-729, 715/864; 710/1, 5, 8; 713/1, 600; 455/11, 455/1.7, 73, 344-347, 93, 95; 370/342-344; 369/1, 2, 6, 12; 463/43-47; 273/148 B**

(57) **CLAIM**

We claim the ornamental design for an media device, substantially as shown and described.

DESCRIPTION

FIG. 1 is a top perspective view of a media device showing our new design;

FIG. 2 is a top view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.

The broken lines are environmental only and form no part of the claimed design.

UNITED STATES PATENT AND TRADEMARK OFFICE
CERTIFICATE OF CORRECTION

PATENT NO. : Des. 601,583 S
APPLICATION NO. : 29/265955
DATED : October 6, 2009
INVENTOR(S) : Bartley K. Andre et al.

Page 1 of 1

It is certified that error appears in the above-identified patent and that said Letters Patent is hereby corrected as shown below:

On the Title page item [75] In the Inventors section on the patent's first page:

Currently:

Douglas B. Salzger, Menlo Park, CA (US)

Calvin O. Seid, Palo Alto, CA (US)

Eugene Anthony Whang, San Francisco, CA (US)

Should be:

Douglas B. Satzger, Menlo Park, CA (US)

Calvin Q. Seid, Palo Alto, CA (US)

Eugene Antony Whang, San Francisco, CA (US)

Signed and Sealed this

Sixteenth Day of February, 2010

David J. Kappos
Director of the United States Patent and Trademark Office
